COOLING SYSTEM

Earle S. Read, New York, N. Y., assignor of one-fourth to Jos. M. Sanders, Jr., as trustee for himself, J. H. Shott, A. G. Fox, A. L. Tyree, and C. W. Freeman, all of Bluefield, W. Va.

Application July 19, 1928, Serial No. 293,920
Renewed July 27, 1933

3 Claims. (Cl. 123—170)

- My invention relates to refrigeration, and more particularly to the application of refrigeration to parts of machinery where cooling is desirable or essential for the proper operation thereof.
- 5 The difficulty of cooling parts of machinery has always been a hindrance in the design and construction thereof. One particular industry in which the cooling problem has played an important part is that of the design and manufacture of internal combustion engines.
- In this field, two predominating methods of cooling have been developed along with the industry, that of circulating water through jackets surrounding the parts to be cooled and that of 15 circulating a current of air over the exposed parts of structure. Each of these systems has advantages and disadvantages over the other. In the case of air cooling, it is necessary to provide the parts to be cooled with fins or other means for 20 increasing the surface exposed to the cooling air. With air cooling there is a greater tendency to overheat than with water cooling, but there is the advantage of the absence of an intermediate cooling medium which may cause trouble from freezing or overheating from evaporation.
- 25 Engines to be water-cooled must be provided with jackets sufficiently large to insure proper cooling with the temperature drop available. The jackets must be cast of material sufficiently thick 30 to prevent fractures due to the cooling medium freezing therein. In casting cylinders adapted to be water-cooled, many difficulties are met, resulting in fairly high cost of production.
- In utilizing the water-cooling system, it is necessary to provide a radiator of sufficient capacity 35 to prevent overheating of the engine when under load. Radiators are usually made of copper, or alloys containing copper, to secure an efficient heat transfer from the air through the radiator 40 to the water. As is well known, a radiator for an ordinary internal combustion engine weighs considerable and is relatively expensive.
- The deficiencies of the cooling system now in common use is more pronounced when such systems are applied to engines of racing automobiles, 45 for instance, wherein a maximum amount of cooling is desirable with apparatus of minimum weight. In some cases, the cooling systems of racing automobiles have been supplied with cubes 50 of ice to keep the temperature of the water from becoming excessive, but even then, after a time excessive temperatures have been reached.
- Another system of cooling is that utilizing the latent heat of evaporation of water. It can be seen that this system inherently contains many 55 of the disadvantages of the water cooling system and for that reason is not decidedly advantageous thereover.
- An object of my invention is to provide a cooling system for an internal combustion engine that
- lacks the disadvantages of systems heretofore used.
- Another object of my invention is to provide a cooling system for an internal combustion engine wherein a refrigerant is expanded in direct heat 65 exchange relation with the parts to be cooled.
- Another object of my invention is to apply a refrigerating system to machinery in general to permit operation thereof at high speeds.
- With these and other objects in view which may 70 be incident to my improvements, the invention consists in the parts and combinations to be hereinafter set forth and claimed, with the understanding that the several necessary elements comprising my invention, may be varied in construction, proportions and arrangement, without departing from the spirit and scope of the appended 75 claims.
- My invention contemplates cooling parts of internal combustion engines and other machinery to insure the proper operation thereof, even under extremely adverse operating conditions. In cooling the internal combustion engine or other machinery a refrigerant is compressed, 80 condensed and expanded into a chamber mounted in heat exchange relation with the parts to be cooled. In applying my invention to an internal combustion engine such as would be used in an automobile, a compressor is mounted in a suitable manner on the frame thereof, and is adapted 85 to be driven by the engine. A suitable drive is provided which may be operated to vary the speed of the compressor and consequently the output 90 of the refrigerating system under varying loads applied to the engine.
- When an internal combustion engine is cooled according to my invention, all disadvantages inherent in the systems heretofore used are eliminated, and as there is no water used, the danger 95 from freezing is entirely avoided. In this respect, however, my invention is much more advantageous than the air cooling system in that a greater cooling rate can be obtained than with the air-cooled system.
- The different pieces of apparatus constituting 100 the refrigerating system employed in carrying out my invention may be arranged in any manner most desirable and adaptable to the particular engine to which it is applied, also the moving parts may be connected with the power shaft of 105 the engine by any means commonly used in transmitting power from a source to a point of utilization.
- While in the following description a preferred 110 form of my invention will be described in detail, it will be clear that many modifications can be made and yet be within the scope of my invention.
- The invention can be best understood when 115 considered with the following description, and in 120

connection with the accompanying drawings in which

Fig. 1 shows a side elevation of an internal combustion engine with my novel cooling apparatus applied thereto.

Fig. 2 is a plan view of the internal combustion engine shown in Fig. 1.

Fig. 3 is a detailed view showing the arrangement of the cooling coils on the cylinders and the valve chambers.

Fig. 4 is a view similar to Fig. 3 showing a slightly modified form.

Fig. 5 is a view similar to Fig. 3 showing still another modified form.

Fig. 6 is a detailed sectional view of a bearing provided with chambers for a refrigerant.

Fig. 7 is a sectional view taken on line 7—7 of Fig. 6.

In Fig. 1 of the drawings, a conventional internal combustion engine 1 of the multicylinder overhead valve type is shown adapted to be cooled by a refrigerating system. The particular refrigerating system shown in Fig. 1 is of the type wherein a gaseous refrigerant is compressed and cooled to liquefaction and the liquefied gas expanded into expansion chambers, to thereby cool objects in contact with said chambers and from which the refrigerant is returned to a compressor.

As shown in the drawings, a compressor 2 is driven by the crank shaft of the engine through a suitable pulley and disc arrangement which will be described later. Compressor 2 is connected by means of a flexible connection 3 with an air cooled condenser 4 in which the gaseous refrigerant compressed in the compressor is condensed.

The condenser 4 is shown mounted on the side of the engine but it may be placed in any position, at any point on the vehicle carrying the engine. As there is no need for a water-cooling radiator on an automobile provided with my invention the condenser 4 could be placed in the forward part of the vehicle in the place usually occupied by the radiator. The condenser 4 can also be mounted under the engine where it will be subjected to the cooling effects of the air currents as the automobile is moving. As shown in the drawings, the tubing forming the condenser is provided with cooling fins 4' to secure a more efficient transfer of heat from the air surrounding the condenser to the refrigerant therein.

The condenser 4 is connected with a receiver 5 to which the fluid condensed in the condenser is adapted to flow by gravity. The receiver 5 may be arranged in any desirable place on the vehicle, but is preferably mounted in such a relation to the condenser to permit the condensed refrigerant to flow thereinto by gravity. The arrangement of parts may be decided on, upon the application of the refrigerating system to various types of engines.

A suitable valve 6 mounted on one end of the receiver 5 controls the amount of refrigerant admitted to a conduit 7, arranged to conduct the refrigerant to a plurality of expansion valves 8. The valves 8 may be of any suitable type, although it is preferable to use the type of valve that is so constructed that none of the refrigerant can escape from the system to the atmosphere. One form of the preferred type of valve is that in which the needle element is operated through a diaphragm sealing the element from the operating means.

As shown in Fig. 1 the expansion valves 8 are placed to supply refrigerant to groups of two cylinders. By this arrangement one expansion valve provides a controlling means for supplying the refrigerant to the two cylinders. Each of the expansion valves is provided with an inlet 9 and an outlet 10 which communicates with the expansion chambers in each group of cylinders. Each of the expansion valves is provided with a valve stem 11 on which is mounted a gear wheel 12. The shaft 13 is carried by supports 14 mounted on the cylinder block of the engine. Mounted on the shaft 13 are suitable pinions 15 adapted to mesh with the gears 12 on the stems of the expansion valves. Shaft 13 carrying a hand wheel 42 is adapted to be extended through the dash of the automobile in which the internal combustion engine is carried, so as to provide an easily accessible means for controlling the expansion valves 8 in unison.

Connected with each of the expansion valves 8 is a plurality of expansion chambers, arranged in heat exchange relation with the parts of the engine to be cooled. Each group of expansion chambers supplied with refrigerant through the valves 8 is independently connected by suitable conduits 37 with a manifold 38 adapted to return the expanded refrigerant to the compressor 2. The manifold 38 is communicatingly connected to the compressor 2 through a flexible coil member 39.

The compressor is provided with intake and discharge valves 40 and 41 which are of a conventional type and need not be described in detail.

When in operation, the refrigerant is compressed by the compressor 2 and passed to the condenser 4, wherein it is condensed and from which it flows into the receiver 5. The valve 6 is regulated to meet the conditions to be imposed on the system. Valves 8, when assembled, are adjusted so that they may be equally controlled in unison, to admit an equal amount of refrigerant to each group of cylinders supplied by each valve. The valves 8 are adjusted by turning the hand wheel 42 until the proper adjustment is had to secure the amount of refrigeration desired. The refrigerant after expansion is withdrawn from the expansion chambers into the manifold 38 and back to the compressor 2 to be recompressed and recirculated.

One form of expansion chamber similar to that illustrated in Fig. 1 is shown in detail in Fig. 3 in which a coil 16 is adapted to convey an expanding refrigerant about a valve chamber 17 of a cylinder 18. After a fluid flows through the coil about the valve chamber, it is adapted to flow through the expansion coil 19 mounted about the cylinder 18. In order to retain the coils 16 and 19 in their correct positions, suitable grooves are provided in the walls about the valve chambers 17 and about the cylinder 18.

By referring to Fig. 2, the manner in which the coils conducting a refrigerant are arranged on the cylinders and valve chambers, can be more readily understood. A conduit 43 connects the expansion valve 8 with the coil 16 about an exhaust valve chamber of one of the cylinders A of the group of two. The coil 16 is connected by a suitable conduit with coil 16' about the exhaust valve chamber of the other cylinder B of the group of two. The coil 16' is connected with a coil 16'' arranged about the inlet valve chamber of the cylinder B and the coil 16'' is connected with coil 16''' about the inlet valve chamber of the cylinder A.

Coil 16³ is connected by a conduit 44 with the coil 19. As shown in Fig. 2 the coil 19 consists of a conduit which is helically woven around and between cylinders A and B. The coil 19 starts at the upper portion of cylinder A, extends around the same between cylinders A and B, over around cylinder B, back between the cylinders, around cylinder A, etc., until an amount of tubing is placed in heat exchange relation with the cylinders to effect sufficient cooling of the cylinders under the conditions to which they will be subjected. By so arranging the coil on the cylinders, it takes the form of a figure 8.

With an arrangement of cooling coils just described, the refrigerant will first enter the coils about the exhaust valve chambers of cylinders A and B, and then will flow to the coils about the inlet valve chambers and thence to the coils about the cylinders A and B. Such an arrangement is desirable, particularly since the coolest refrigerant is supplied to the exhaust valves which require the greatest amount of cooling. The manner of arranging the coils may be modified to suit the application of the cooling system to various types of engines. In some cases certain coils may be eliminated and certain other coils may be increased in capacity to afford a greater amount of cooling.

A slightly modified form of my invention is shown in Fig. 4 which differs from that shown in Fig. 3, in that the expansion chamber about the valve chambers consists of a jacket 20, rather than a coil 16 as shown in Fig. 3. There may be certain instances when such an arrangement may prove desirable over one such as shown in Figs. 1, 2 and 3. In Fig. 4, the expanding refrigerant enters the jacket 20 through an inlet 21. After flowing through the jacket 20, the refrigerant is conducted by means of a conduit 22 into a coil 19' identical with that shown in Fig. 3, mounted about the cylinder 18'.

Fig. 5 shows still another modified form of my invention in which both the valve chambers and the cylinder are provided with jackets rather than coils such as shown in Fig. 3. In the form of this invention the refrigerant enters the jacket 23 about the valve chamber through a suitable inlet 24 and then flows downwardly into the jacket 25 about the cylinder 18² and from there back to the refrigerating system through a suitable conduit 26.

My invention also contemplates the cooling of the bearings of an internal combustion engine or of any other machine by expanding a refrigerant in heat exchange relation therewith. One form of an arrangement for cooling bearings is shown in Fig. 6 in which a support 27 for shaft 45 carries a bearing seat 28. The bearing seat is provided with a suitable space or jacket 29 in which a refrigerant is adapted to expand. Mounted on the bearing seat is a bearing 30 of babbitt or other suitable bearing material. The cap 31 is provided with a jacket 32 similar to jacket 29 in the bearing seat 28. The cap 31 also carries bearing material such as 33 similar to that indicated at 30 in the fixed part of the bearing. A conduit 34 connects the jacket of the fixed half of the bearing seat with the jacket in the cap of the bearing in such a manner as to provide for the flow of a refrigerant therethrough from one jacket to the other. An inlet 35 places the jacket 28 in communication with the supply line from the refrigerating system, and the conduit 36 places the jacket 32 in com-

munication with the return line of the refrigerating system.

When it is desirable to cool the bearings of an internal combustion engine, bearings similar to those described, or of any type having chambers in which a cooling medium can be circulated are provided and the expansion chambers are connected by suitable conduits and valves with a refrigerating system such as shown in Fig. 1. The refrigerant may be admitted to the bearing directly from the refrigerant supply line or may be first circulated through the coils surrounding the cylinders and valve chambers and then into the jackets of the bearings.

Bearings similar to those just described may be applied on any type of machine in which bearings are necessary. By using a bearing of such type, cooled by an expanding refrigerant, extremely high speeds may be attained without the danger of burning out bearings or scoring the shaft. Such usage is particularly advantageous when it is desirable to increase the speed of a machine above that for which it is designed, in order to meet the demands of an overload.

In some installations, particularly when applied to an internal combustion engine of an automobile, it is desirable to have some means for automatically controlling the amount of refrigeration applied to the parts to be cooled. One method of accomplishing this result would be to provide a thermostat for controlling the speed of the compressor. Another method of accomplishing the same result is by utilizing a means for affecting the speed of the compressor upon variation in the grading of road over which the automobile is travelling.

Apparatus for carrying out the last method is shown in Figs. 1 and 2, in which the compressor 2 is mounted on a slotted base 46, over which it is adapted to slide. A pendulum 47 provided with a weight 48 of sufficient mass for the purpose for which it is supplied, is pivotally mounted at 49 to the frame of the engine 1. The free end of the pendulum is provided with a pin adapted to engage in a slot 50 of a link 51 carried by the compressor 2.

A disc 52 is mounted on the drive shaft of the compressor 2, and is arranged with relation to the frusto-conical pulley 53 as to be rotated upon any rotation of the pulley 53. The frusto-conical pulley 53 is mounted on a spindle which is rotatably carried by a suitable extension of the gear housing 54 of the engine. A grooved pulley 55 is also mounted on the spindle carrying the pulley 53 and is connected by a belt 56 with a power pulley 57. Thus, when the engine is running, power is transmitted through the pulley 57, belt 56, pulley 55 and the spindle to the pulley 53, which in turn imparts rotation to the disc 52 to operate the compressor.

As before stated, the compressor is slidably mounted on the base 46 and in such a manner that the direction of travel of the compressor when slid, is parallel to the surface of the disc 52. By causing the compressor to move in a path parallel to the surface of the disc 52, the same degree of frictional engagement will be maintained between the disc 52 and the pulley 53, thus insuring a smooth supply of power to the compressor.

In order to prevent wear on the pulley 53, it is made frusto-conical, the angle of the slope of the cone surface relative to the base thereof being such that there will be no tendency of either the surface of the pulley 53 or the disc 52 to

be distorted. The material of which the pulley 53 is constructed, should be one capable of insuring an efficient frictional engagement between the pulley and the disc.

5 When in operation and the vehicle is running on level ground, the compressor will be in the position shown in Fig. 1. If, however, the vehicle starts up a grade, the pendulum 47 will tend to rotate counterclockwise and slide the compressor forward on its base. By so moving the compressor, the pulley 53 will engage on the disc nearer the center thereof. It is obvious that by changing the relation of the disc and pulley as described, the speed of the compressor relative to that of the pulley 53 will be materially increased.

10 The flexible coils 3 and 39 are provided to permit movement of the compressor without rupture of any of the tubing or other parts of the system.

15 It should also be noted that the pin and slot connection between pendulum 37 and link 51 permits slight movement of the pendulum such as caused by road shocks, etc., without affecting the speed of the compressor.

20 Although I have described the drive to the spindle by a belt, I have done so merely by way of illustration and I may use any other type of drive commonly used for similar purposes, such as by chain or gears. Also, any type of speed-varying mechanism may be used to vary the speed of the compressor under varying conditions.

25 In the foregoing description, I have described a compression system of refrigeration in which the liquefied refrigerant is expanded through a valve into a chamber, but I wish it to be understood that my invention contemplates the utilization of other forms of refrigeration. It may sometimes be desirable to use the "flooded" system of refrigeration, that is wherein a liquid refrigerant is circulated throughout the expansion coil. This type assures the same degree of cooling throughout the entire expansion chamber, as the mixture of liquid and gas reaches all points in the expansion chamber.

30 In some installations of a refrigerating system on an internal combustion engine to cool the same, it is desirable to utilize the equipment already on the engine. One method of such an application is to circulate the refrigerant through coils located in the jackets surrounding the parts of the engine to be cooled and to circulate a cooling medium through the jackets. With such an installation, it is essential that some cooling medium be used that will not congeal upon contacting with the coils containing the refrigerant. For this purpose water is impractical, due to its relatively high freezing point. Solutions having low freezing points, such as those containing alcohol, glycerine or other substances capable of lowering the freezing point of water, can be effectively used for this purpose.

35 With such an application, any of the distinct types of refrigerating systems may be used for cooling the so-called non-freezing solution circulating through the jackets.

40 My invention also contemplates the application of an absorption type of refrigerating system to an internal combustion engine, thereby eliminating the use of a compressor. When using types of refrigerating systems other than that shown in the drawings, it may be desirable to circulate the refrigerant through the coils in a direction different from that shown, but such an arrangement

could be easily made to meet the requirements of the particular type of refrigerating system used.

45 In utilizing any type of refrigerating system to carry out my invention, I intend to use a refrigerant that will produce a maximum amount of cooling per pound of refrigerant. By using such a refrigerant, the apparatus to produce the refrigerating effect can be relatively small, particularly as compared to a system using ammonia as a refrigerant.

50 In operation, the internal combustion engine is provided with apparatus as described, and when the engine is started, the compressor 2 starts working to compress the refrigerant which is condensed in the condenser 4 and passed to the receiver 5.

55 The refrigerant is conducted from the receiver to the expansion valves 8, which act to maintain a sufficient pressure difference to produce an expansion necessary for the refrigerating effect. The refrigerant is expanded into the coils 16 about the exhaust valve chambers which are connected in series with coils about the intake valve chambers and coils 19 about the cylinders. If desirable, the refrigerant can be further circulated to jackets about bearings of the engine, constructed as shown in Figs. 6 and 7.

60 From the last cooling coils, the refrigerant is conducted to the return line 38 and thence back to the compressor, to be recompressed and recirculated. As shown in Fig. 1, the compressor is in a position at which it will run at the lowest speed relative to that of the engine. When the vehicle carrying the engine is run up an inclined road, the pendulum 47 will operate to move the compressor 2, so that the position of the disc 52 will be changed, thereby changing the speed ratio to cause the compressor to operate at a somewhat higher speed compared to that at which it operated before it was moved.

65 While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention or exceeding the scope of the appended claims.

70 I claim:

1. In combination with an internal combustion engine, chambers in heat exchange relation with parts of said engine, a refrigerating system for introducing an expanding refrigerant into said chambers and means responsive to an increase in the load on said engine for increasing the rate of flow of said refrigerant.

75 2. An internal combustion engine comprising a plurality of cylinders, chambers arranged in heat exchange relation with said cylinders, an expansion valve for each chamber, and means for operating said expansion valves in unison.

80 3. In combination with an internal combustion engine chambers in heat exchange relation with parts of said engine, a refrigerating system for introducing an expanding refrigerant into said chambers and means responsive to an increase in the load on said engine for increasing the rate of flow of said refrigerant, said means comprising a pendulum adapted to vary the drive ratio between a power shaft and a compressor for said refrigerant.

85 EARLE S. READ.
